Attorney.

UNITED STATES PATENT OFFICE.

THOMAS OCTAVE MURDOCK SOPWITH, OF KINGSTON-ON-THAMES, ENGLAND.

WIND-SCREEN FOR USE WITH AIRCRAFT-GUNS.

1,249,535.

Specification of Letters Patent. Patented Dec. 11, 1917.

Application filed August 14, 1917. Serial No. 186,232.

To all whom it may concern:

Be it known that I, THOMAS OCTAVE MURDOCK SOPWITH, commonly known as THOMAS SOPWITH, a subject of the King of Great Britain and Ireland, residing at Canbury Park Road, Kingston-on-Thames, in the county of Surrey, England, have invented a certain new and useful Improved Wind-Screen for Use with Aircraft-Guns, of which the following is a specification.

This invention relates to an improved wind screen for use with guns employed on aeroplanes and other aircraft, and it has for its object to provide a suitable rest for the head of the person operating the gun and to provide a cushion around the screen so as to minimize accidental damage to the gunner by impact or concussion with the screen either in case he becomes unconscious or from shock arising from too rapid a landing.

I attain these ends by providing on the back of the frame of the screen a pad or cushion which preferably takes the shape of said frame and entirely covers same, but this is not obligatory.

In the accompanying drawing which illustrates this invention:—

Figure 1 is a view in side elevation showing the improved screen fitted to a gun, and Fig. 2 is a view in front elevation of the screen.

In both views similar parts are marked with like letters of reference.

The improved screen comprises a D- or other suitably shaped frame *a* which carries a pane of glass or other like and suitable material and a pad or cushion *b* on the rear or back of the frame *a*. The screen is attached to the gun by means of lugs *c* which are carried by the frame *a* either directly, or indirectly as shown in the accompanying drawing by means of horizontal cross bars *a*¹ and vertical cross bars *a*², said lugs being fixed by means of bolts or screws to suitable brackets *d* carried by the gun, which is shown in dot-and-dash lines in Fig. 1.

The pad or cushion *b* may be stuffed with any suitable material such as kapok, or said

packing or padding may take the form of a pneumatic tube.

It will be seen that the pad or cushion carried by the screen forms a convenient rest for the head of the gunner when sighting or firing the gun and that it also forms a protection from concussion by accidental contact with the screen.

What I claim as my invention and desire to secure by Letters Patent is:—

1. In a wind screen for aircraft guns, the combination of a frame adapted to be mounted on the back of the gun, a glazed transparent panel carried by said frame, and a pad or cushion mounted on the back of said frame.

2. In a wind screen for aircraft guns, the combination of a frame, a pane of glass or the like mounted in said frame, a pad or cushion mounted on said frame, and means for attaching said frame to the gun.

3. In a wind screen for aircraft guns, the combination of a D-shaped frame, a glazed panel carried by said frame, a pad or cushion mounted on and covering the back of said frame, and means for mounting said frame on the gun.

4. The combination with a gun employed on aeroplanes and other aircraft, of a wind screen the face of which through which the gunner looks being provided with a pad or cushion, as set forth.

5. The combination with a gun for aeroplanes and other aircraft, of a frame adapted to be fixed on the gun, a glazed panel carried by said frame, a pad or cushion mounted on said frame, and means for attaching said frame to the gun.

6. In a wind screen for aircraft guns the combination of a frame *a* glazed with glass or other suitable transparent material, a pad or cushion *b* on the rear of said frame, lugs *c* on the front of said frame, and a bracket *d* mounted on the gun and adapted to receive the lugs *c*.

In testimony whereof I have signed my name.

THOMAS OCTAVE MURDOCK SOPWITH.
